UNITED STATES PATENT OFFICE.

LOUIS B. MOORHOUSE, OF TOLEDO, OHIO.

METHOD OF GENERATING WATER GAS.

Application filed July 19, 1920. Serial No. 397,378.

My invention has for its object to provide an apparatus and method whereby producer gas and water gas may be efficiently and economically manufactured from coal or coke or similar material and wherein the objectionable features usually found or met with in the manufacture of such gases are greatly reduced. By my invention is provided a means and method whereby practically all 10 of the gas producing elements of the fuel are utilized or recovered. Thus the apparatus and the method efficiently produce the gases from the fuel.

My invention particularly has for its object to prevent the formation of clinkers and the loss caused by the improper or incomplete utilization of fuel during the operation of the apparatus and also to convert the products of incomplete gasification, such 15 as tar and the like, into available form which products otherwise in apparatus now known in the art, are largely lost. My invention thus particularly provides a means and a method for controlling or preventing 20 clinker formation and also provides for the proper distillation of the hydrocarbon materials in the fuel body. The gases are discharged from the relatively cold fuel body, while they are in condition of reaction into 25 the hotter fuel wherein they are decomposed to form larger quantities of the gas. Thus by my invention is provided a means for further cracking or breaking up the hydrocarbon materials to form additional gas and 30 the production of a cleaner gas.

My invention not only has for its particular object to control or prevent the clinker formation, but also to prevent the formation of "chimneys" or "blow holes" in the body 35 of the fuel and thus eliminate intense local reaction. By my invention is provided a means and method of operation whereby there is a uniform descent of fuel to the reaction chamber or chambers and also wherein 40 by the region of reaction is maintained in a definite position in the generator. My invention also particularly has for its object to provide a means for obtaining the gases with increased efficiency from finer and 45 cheaper fuel and of obtaining the required time of contact of the gases with the heated fuel and yet wherein the flow of the air or steam or both will still be of substantially the requisite rates through the fuel for the 50 production of the gases and complete consumption of the fuel.

By my invention is also particularly provided a producer gas and water gas apparatus which may be continuously operated by reason of the fact that clinker formation 60 is practically obviated and in this connection I have provided means whereby the ash may be discharged without discontinuance of the operation of the apparatus which results in a great saving of the fuel and an increased 65 production of the gas. The invention also has for its object other advantages and features which will appear from the following description and upon examination of the drawings.

The invention may be contained and performed in generators and apparatus of different forms and the parts thereof connected up in different ways. To illustrate a practical application of the invention, I have 70 selected one or two forms of construction containing the invention and shall describe them hereinafter. The constructions selected are illustrated in the accompanying drawings.

Figure 1 of the drawings illustrates a top view of one of the constructions selected as an example of apparatus containing my invention. Fig. 2 is a sectional view taken on the line 2—2 indicated in Fig. 1. Fig. 3 is 75 a sectional view taken on the line 3—3 indicated in Fig. 2. Fig. 4 is a sectional view taken on the line 4—4 indicated in Fig. 2. Fig. 5 is a top view of a means for securely and quickly closing the regenerators. Fig. 6 is a side view of the stack closing valve 80 illustrated in Fig. 5, partly in section showing the valve open. Fig. 7 is a side view of the stack valve showing the valve closed. Fig. 8 is a top view of a modified form of 85 construction containing the invention. Fig. 9 is a sectional view taken on the line 9—9 indicated in Fig. 8. Fig. 10 is a diagram showing a relation of the currents of gas or vapor that may be directed through the generator. Fig. 11 is a sectional view taken on the line 11—11 indicated in Fig. 9.

The fuel is consumed in a generator 1 in the production of the gas. The fuel is fed into the generator through the hoppers 2. 105 The hoppers are provided with suitable gates 3. Drums 5 are located below the hoppers and receive the fuel from the hoppers. The lower ends of the drums are closed by the distributing cones 4 which distribute the 110 fuel within the top of the generator and so that it will not collect in a conical pile. The

generator is kept closed either by the gate 3 or the cone 4. The drum 5 may be filled when the cone is closed, but when the cone is opened the gate 3 is closed. By this arrangement the fuel may be fed into the generator without loss of gases and without interruption of the reactions that take place in the generators.

The generators of the different forms shown in the drawings are also provided with ash receivers or troughs 6 in which water may be inserted for sealing the lower ends or bottoms of the generators and thus preventing the escape of gas through the ashes to the atmosphere, and also to prevent air entering. The walls 7 in each case are secured to the supporting columns 8 and extend well into the trough 6 so that notwithstanding the ordinary pressure of the gases within the generator the generator will be sealed from the atmosphere by the water and escape of gases from the generator prevented as well as the entrance of the air from the atmosphere through the ash chamber avoided.

The generators may be also provided with ash chambers having sloping walls 9 that terminate at their lower ends in proximity to each other and so as to form narrow passageways between the lower edges of the walls 9. Beneath the opening 10 formed between the lower edges of the walls 9 is located a suitable movable grate or the equivalent thereof, in each generator, whereby the desired quantities of ash may be from time to time withdrawn from the ash chamber through the opening or passageway 10. In the constructions shown a sector rotative grate member 11 is located beneath and in proximity to the lower edges of the walls 9 which will prevent normally the downward movement of the ash but which upon oscillation will allow the ash to drop into the trough 6 of the generator.

The trough 6 is preferably provided with an inclined bottom portion 12, the lower end of which is located well below the edge of one of the side walls 7 and the corresponding side of the trough 6 is located slightly remote from the said walls 7 to permit the insertion of a hog or rake or other suitable mechanical means to draw the ashes down the inclined portion as they are discharged by reciprocatory movements of the grate member 11. The trough 6 may also be provided with a receiving chamber 13 that is located at the lower end of the inclined portion whereby the ashes that collect in the receiving portion or chamber of the trough 6 may be mechanically removed.

The apparatus is provided with the regenerators 14 and 15 which are constructed in the manner well known in the art, and which are shown conventionally in the drawings.

They have the usual checkerwork, not shown

in the drawings, for alternately heating streams of air or steam and being heated by exhaust gases in the manner well known. The generator 1 in the form of construction illustrated in Fig. 1 is provided with headers 16 wherein the gases may be received from the generator to permit settling of the sediment such as fine ash or dust. They prevent the deposition of ash in the regenerators 14 and thus prevent fusion of the brick forming the checker work contained therein. The hot gases pass through the regenerators 14 and 15 and if the apparatus is provided with the headers 16 they also pass through the headers 16.

During alternate periods in the operation of the apparatus, air is directed through the sets of regenerators 15 and 14 located on one side of the generator. Air under pressure is admitted to the regenerator 15 and forced through the checkerwork of that regenerator and through the regenerator 14 to the gas generator. The products of combustion pass out through the set of regenerators 14 and 15 located on the other side of the generator which may be opened to the atmosphere or stack through the regenerator 15 if water gas is being formed. When, however, producer gas is being formed, the regenerators 15 are maintained closed from the atmosphere at all times. Inasmuch as the movement of the air is through the regenerators on one side during one period of the operation and then through the regenerators on the other side during a subsequent period of operation, and inasmuch as the hot gases under considerable pressure pass through the regenerators into the gas collecting main during intermediate periods, I have provided a means whereby the regenerators 15 may be quickly closed and yet also whereby the closing means may be securely locked in the closed position.

The means for closing each of the regenerators 15 consists of the shell 17 having a valve seat 18 located at its upper end. The stack valve member 19 is provided with a recess having a heat resisting packing 20 such as asbestos located in an annular channel formed on the under side of the valve member 19, and so as to cover a ridge 21 formed on the upper end of the shell 17. The valve member 19 is provided with a yoke 22 that extends over the top of the valve member and to the ends of which are pivoted links 23. Links 24 are also pivoted to the sides of the shell and at points such that when the valve member 19 is closed, the pivot points of the links 23 to the yoke 22 will be substantially in the same vertical line in which the pivot points of the links 24 to the sides of the shell 17 are located. The links 23 and 24 are also pivotally connected together and at points which are substantially in the same vertical lines that pass through the other pivot points of the links.

and which when the valve is closed will be located below the other said pivot point.

Means are provided for drawing the link 23 downward and so as to swing the links 23 towards the links 24. By this arrangement there will be a toggle action as between the links 23 and 24 and their points of connection with the valve member and the shell respectively. Thus the valve member may be 10 quickly drawn to its seat, and, during a portion of the movement of the lower ends of the links 23 and the valve member, will be tightly sealed on its seat. To operate the links 23 I have provided reciprocating bars 15 25 that may be yoked together by means of the yoke 26 and thus operated in unison. The links 23 are connected to the bars 25 by means of the links 27 of a length sufficient to cause the links 24 to rotate on their pivotal connections to the shell 17 which operates to raise the lower ends of the links 23 and 24 and consequently to raise the valve 19. The link 27 is of a length sufficient to raise the ends of the links 23 and 24 to near 20 the upper end of the shell 17 which throws the valve to a wide open position. Upon the return movement of the yoke 26 the links 23 and 24 are drawn down which swings the valve 19 down to its seat and at the same 25 time brings the pivotal points of connection between the links 23 and 24, substantially at right angles to the direction of movement of the bars 25 which brings the valve member 19 down on its seat under a pressure obtained 30 by the full force to which the bars 25 are subjected as well as by the toggle relation between the links 23 and 24 and the shell 17 and the valve member 19.

Under certain conditions or operations, 40 such as in forming water gas, the regenerators 15 are alternately connected by means of the valves 31 with the main 30 through which air under pressure is supplied to one or the other of the regenerators 15. The air 45 passes through the checkerwork, not shown, in the regenerator 15 and through the checkerwork, also not shown, in the regenerator 14 connected with the said regenerator 15. It then passes from the regenerators 14, through 50 the valves 32 and the pipes 33 into the generators, as hereinafter described.

Under certain conditions of operations or to accomplish the performance of certain reactions, air may also be admitted through 55 the valve 34 located in the pipe 35 and thus conducted to the generator. The steam enters through the steam supply line 36 and is admitted to the regenerators 15 through the valves 37 and is superheated as it passes 60 through the checkerwork located in the regenerators 14 and 15. During the alternate periods, the steam passes through the valves 32 and 34 and enters the generator. Also if desired, a valve 38 may be opened which 65 will permit steam to enter the generator

through the pipe 39. If desired, unsuperheated steam may be conducted through the pipes 40 and the pipe 39 to the generator. Also the pipes 42 may be connected with the main air supply pipe line 30 and to the regenerators 14 which may be directly connected to the generator as in the form shown in Fig. 8, or they may be connected to the generator through the header 16 as shown in Fig. 1 where the combustible portion of the products may be further consumed by the additional air admitted through the pipe 42. The ports and generator connections with the parts of the system exterior to the generator are particularly described hereinafter, together with the functions that they perform in connection with the generator.

If desired, the pipes 39 may be connected through valves 44, with a pipe line 45 which is maintained at a pressure below the pressure of the interior of the generator by means of an exhauster. By opening one or the other of the valves 44, certain hydrocarbons distilled by the heat of the burning fuel may be drawn up through the body of the fuel 90 and precipitated by becoming chilled while at the same time certain of the more volatile matters of the coal will pass off with the gaseous hydrocarbons through the pipe 45 and one or both of the pipes 39. If it is 95 deemed undesirable to recover volatile hydrocarbons in this manner they are directed downwardly and "cracked" in the hotter regions of the generator and go out through the pipes 35 through the valve 34 and the regenerators 14 and 15, and through the valves 46, and the pipe line 47, to suitable storage reservoirs or consuming devices.

The construction is such that in the production of either producer gas or water gas, lignite or bituminous, preferably non-coking, coal may be used.

If lignite is used as fuel its high moisture content readily breaks it up under heat into small particles and thus it offers high resistance to gas flow. It may, however, be economically gasified in the type of apparatus illustrated in Figs. 1, 2 and 3. Since the direction of flow of the reacting gases is downward through the incandescent fuel the moisture of the lignite is dissociated through the usual water gas reaction and not merely vaporized. The coal enters the fuel receiving chamber 50 from the drums 5 and collects above the bridges or partition walls 51 which are closely positioned in order to reduce the length of the gas or air or steam currents that are directed transversely and downwardly through the fuel. By this construction a finer fuel, and consequently a cheaper fuel, may be used. Also a coal that breaks up into finer parts may be used. Also by reason of the location of the bridges 51, localization of drafts, or the formation of chimneys or blow holes through the coal 130

is prevented since the ports of the generator which are located in the bridges and the side walls are closely positioned and the side walls and the bridges operate to constantly 5 disturb the relation of the particles of the fuel by reason of the relatively continuous downward movement and the closely positioned bridges. Moreover the bridges 51 have opposing surfaces that slope down- 10 wardly away from each other, which also operate to cause the fuel 90, as it approaches the main reaction chamber 91, to loosen up and permit relatively free passage of the gases, air and steam, which thus permit 15 ready mingling of the gases, air and steam, with the partially consumed fuel and with the unconsumed fuel.

In heating a bed of fuel, in the production of water gas, the carbon of the fuel is first 20 oxidized to a preponderance of carbon dioxide. The carbon dioxide, when passing through the hot incandescent fuel, is reduced by the addition of carbon whereby carbon monoxide is formed. The formation 25 of carbon monoxide from carbon dioxide depends upon the temperature and the time of contact. The air blast operates to elevate the temperature of the fuel and to store heat within the fuel, which heat may be 30 subsequently utilized at such elevated temperature for the formation of water gas through the combination of carbon with the oxygen produced by the dissociation of steam, thus generating carbon monoxide and 35 hydrogen. During the blast or heating period the maximum economy of fuel is effected when the carbon is burned to carbon dioxide, that is to say, when within the fuel the maximum generation of heat per unit of 40 carbon is effected. Inasmuch, therefore, as an increased temperature within the fuel bed is the object of the blasting period, and because of the fact that a long time of contact between products and fuel operates to produce 45 carbon monoxide, which does not produce within the body of the fuel the maximum amount of heat, it is necessary either to decrease the distance of travel or to run the air at a rapid rate through the fuel in 50 order to decrease such time of contact. The latter procedure results in carrying dust and finer particles out of the gas generator. By placing the ports close together, particularly, when a fine fuel is used, the air may 55 be forced through the fuel at such a rate that the lighter particles will not be carried away and yet the maximum amount of carbon dioxide will be formed. This will produce the maximum amount of heat per unit 60 of fuel within the fuel bed preparatory to the passage of the steam through the fuel bed.

The air is directed from the main line 30 into the regenerators 15 and 14 which have 65 been previously heated by the discharge

products of a previous air-blast period and which operate to heat the air. The air passes through the pipes 33 into passageways that lead to the ports 52 formed in the side walls and the bridges of the generator 70 shown in Fig. 2. The air passes diagonally downward from the ports through the fuel bed in the reaction chamber 91 to the lower part of the gas generator side wall and to the edges of the bridges 51 and to the openings or outlet ports 53 formed therein. The air thus passes down across the hot fuel located between the bridges and between the bridges and the side walls 96 of the generator, and the heat and temperature of 80 the fuel is greatly increased. The products that are formed during the movement of the air through the finer fuel pass out through one of the pipes 35 and the valves 34 into the header 16 and thence through 85 the other set of regenerators 14 and 15 and out through the stack valve. During the succeeding period the steam flow may be directed through the same path or it may be directed diagonally down and across from 90 the alternate bridges or generator wall.

Inlet ports 52 of alternate bridges and wall of the generator are connected with one pipe 33 and the other inlet ports 52 are connected with the other pipe 33 and the outlet ports 53 of alternate bridges and wall of the generator are connected with one pipe 35 and the other outlet ports 53 are connected with the other pipe 35. In the constructions shown the inlet port 52 and the outlet port 53 in any single wall or bridge of the generator make connection with the pipe 33 and the pipe 35 which last named pipes are connected to the same side of the generator, as shown in Figures 1, 2, 3, and 100 4. Thereby the flow of air or steam or mixture and steam through ports 52 will be from one set of bridges or wall of the generator to the lower edges of the adjoining bridges or wall, where the said ports 53 are 105 located, during one period and will be from the ports 52 of the other set of bridges or wall of the generator to the lower edges of the adjoining bridges or wall during another period so that in succeeding or subsequent 110 blasts the paths of the air movement will 115 cross the path of flow during preceding periods.

During different periods the directions of flow may be across any one section or unit of the generator in opposite general lateral directions though diagonally downward and through the reaction chamber or incandescent fuel. The connections are such that the flow during one period is from the bridges 120 and one side wall toward the adjoining bridge or side wall diagonally downward to the lower ports, and during different periods, the flow is from the last named bridges and side wall, thus giving a reversal of the gen- 125 130

eral lateral direction in each generator unit, that is, in each space formed between adjacent bridges or bridge and generator wall.

This produces a condition of fuel bed in which that portion of the fuel below the point of crossing of the upper limits of succeeding blasts is substantially entirely incandescent, such condition being illustrated in sectional drawings Fig. 2 and Fig. 9. By this crossing of the paths of blasts, therefore, the volatilized hydrocarbons issuing into the first portion of the paths of the air blasts, are carried downward through fuel left in a state of incandescence by the preceding blast and there broken up and burned before reaching the exit ports 53. The steam may now be directed through the same ports that the air was directed in the preceding operation which will cause the most intimate contact between the steam and the most highly heated portion of the incandescent fuel thereby causing the maximum formation of water gas from the steam and carbon of the fuel which gas passes out through the same ports.

However, it has also been found advisable to admit the steam through the same regenerator through which the products of the preceding air blast were directed and by the intense heat that was produced in the checkerwork during the preceding operation, that is, during the air blast to more highly superheat the steam which will then be directed through the ports 52 of bridges other than those through which the air blast was directed in the preceding operation. The steam thus more highly superheated will cause a greater distillation of hydrocarbons from the coal contiguous to the ports 52 and thereby the products of dissociation of hydrocarbons will bear a higher ratio to those gases formed by dissociation of steam, that is to say, by this procedure there will result an increase in the ratio of hydrocarbons utilized for forming combustible gases to the hydrocarbons utilized for heating the fuel during the blast and ultimately a gas richer in hydrogen and methane or other fixed hydrocarbons will be produced thereby. In the succeeding operation, the air may follow that is may pass through or along the incandescent fuel in the same general direction of the path through which the steam passed in the preceding operation and will be directed through the ports 52 through which the steam was directed in the said preceding operation. The products thereof will be passed through the ports 53 and out through the other regenerators 14 and 15 and through the valve 19. The valve 19 will then be closed and the steam will then be passed back through the last named regenerator into the generator through the ports 52 other than those through which the air passed in the preceding operation. Also

in succeeding steaming periods (gas making periods) the paths of the steam and gases may be caused to cross. This crossing of paths of the currents of steam with the paths of preceding air currents causes the hydrocarbons volatilized in the upper portion of the passage to be dissociated and gasified.

It is to be understood that the paths of the steam flow may cross the paths of the air flow during succeeding periods and also that variations as between water gas and producer gas production may be used to produce various mixtures of water gas and of producer gas. Also that the periods may not be immediately succeeding but may be subsequent and after intermediate periods. It will thus be seen that variations in the operations of the apparatus may be followed and such variations will still be within the scope of my invention.

The movement of the steam, of the air and gases from the ports 52 and 53 causes the movement of vapors through the hot fuel into and through the hotter fuel at lower points in the reaction chamber of the generator with the result that the hydrocarbons are largely decomposed into their elements and thus an increased production of gas is effected and at the same time the gas freed from tar and carbon particles. The carbon will remain in the fuel to be further consumed in subsequent periods of operation of the generator.

By this arrangement the air is directed downwardly into the fuel which produces a maximum heat within the upper portions of the reaction chamber or parts thereof. Inasmuch as the formation of the carbon monoxide from the carbon dioxide is endothermic, such formation, if it occurs, will occur near the ash line which will operate to avoid excess temperature and consequently reduce or eliminate the formation of clinkers near the ash line.

By directing steam through the pipe 40 or superheated steam through valve 38, thence into the generator through pipes 39 by way of ports 56 during the time that the steam is directed into certain of the ports 52; the tarry vapors arising from the distillation of the fuel is directed into the incandescent fuel below, where they will be broken up or cracked to form lighter hydrocarbons and pass out through one set or the other set of ports 53. In this manner, especially if superheated steam is used, a greater quantity of the volatile components are distilled and gasified during the gas making period.

If desirable to separately recover the volatile constituents of the fuel, I have also located ports 56 in the bridges 51 and in the side walls of the generator. The ports 56 are located well above the line between the incandescent fuel and the uncarbonized fuel

and so as to be above the fuel carbonized by the heated fixed gases and vaporous hydrocarbons that rise from the reaction chamber of the generator. The ports 56 are connected with the pipe 39 and through the valves 44, with the reduced pressure main 45. This will operate to draw the volatile elements of the fuel, which are volatilized in the vicinity of the reaction chamber 91 that is, in or in the vicinity of the incandescent fuel, upwards. It will thus draw off a considerable percentage of the lighter hydrocarbon gases and vapors although it will leave in the uncarbonized fuel located intermediate the incandescent fuel and the ports 56, the heavier and higher boiling point hydrocarbons which will be condensed by the chilling action of the cooler fuel in the vicinity of and below the ports 56. This will operate to subject certain portions of the heavier hydrocarbons to repeated vaporization and cracking action near the lower regions and a subsequent condensation in the higher and cooler regions. The decomposition products so formed will pass off through the ports 56 or pass off through the ports 53 during the same or subsequent period of operation of the generator. The tarry products and ammonia contained in the hot mixture so withdrawn through the ports 56 may, if desired, be subsequently separated and collected by the customary means for condensation and separation. By this arrangement the tarry products which would pass into the checkervwork of the regenerators will be prevented from causing an excess of heat in the checkerwork and will be recovered as valuable by-products.

The bridges or partitions and the walls of the generator may be constructed in different ways, but I have found it desirable to so construct the walls and bridges of the generator that the coal in its descent will leave passageways in the vicinity of the ports. In order to accomplish this I have so formed the ports that the upper surfaces of the ports 52 and 56 will overhang the openings so as to prevent the collection of the fuel within the ports and thus prevent the clogging of the ports. In other words, the general direction of the openings that form the ports is downwards so that the downward moving fuel will be carried from the ports and leave a lateral or horizontal passageway over the surface of the fuel. To obtain more uniform flow of gas I have provided perforated arches 57, 58, and 59. The ports moreover may be in the form of slots such as that shown or each port may be formed of a plurality of openings formed by partitioning the slots. Also the lower surfaces of the ported wall may be made sloping as in the case of the ports 56. The ports 53 open from the lower edges of the bridges and the overhanging portions of the walls

of the generator which leave laterally extending passageways beneath the ports 53 to permit a free outlet of the gases.

The generator shown in Figs. 1, 2, 3, and 4, may be used in the production of producer gas as well as in the production of water gas, since in the production of producer gas the air and the steam may be directed through the ports 52 at the same time and consequently the stack valves 19 will be maintained closed at all times. In the operation of the generator there will be the same crossing of the paths of movement of the air and steam from and to the ports 52 and 53, in consecutive periods of operation of the generator. The producer gas will be collected in the pipe 47 in the same manner that the water gas was collected in the pipe 47. Also if it is desired to collect the volatile materials of the coal and the tarry products; they may be drawn out through the ports 56 which are connected with the exhaust pipe 45 in the same manner as in the water gas production.

Also if it is desired, air or steam may be directed through the ports 53 other than those through which the gases are drawn, that is to say, the alternate ports 53 will afford inlets for the steam and air while the other ports 53 will afford outlets for the gases that are produced by bringing the steam in contact with the incandescent fuel and thus produce a lateral sweep of the air and gas or vapor.

The steam from the ports 53 reduces the clinker formation and causes all of the fuel to be consumed. In generators where air is admitted through ash or clinker and directed upward through an incandescent fuel bed, it prevents the proper settling of the finer ash particles and they are carried upward from the ash zone into the hottest portion of the fuel bed. Thus unless large quantities of steam or some other temperature deterrent is used, there exists those conditions conducive to fusion of the ash, which upon subsequent cooling forms clinkers. Solidification of fused ash in the presence of unburned fuel always encases certain quantities of the fuel and prevents the utilization of such encased fuel which greatly decreases the efficiency of the generator. In an effort to control clinker formation the operator will ordinarily use too much steam to prevent the formation of the fused ash and it is practically impossible for an operator to secure the proper balance between air and steam. In the form of construction illustrated and in generators containing my invention, the sweep or flow of gases being generally in a lateral direction near the ash line, obviously none of the ash is carried up into the incandescent fuel and there is nothing to prevent the ash from sifting downward on to the ash bed. The flow of gases

being downward as well as lateral, operate to carry down all ash towards the ash zone, and consequently clinker formation is greatly emolliated.

- 5 The form of generator illustrated in Figs. 8 and 9 is a simplified or single unit apparatus operated in like manner to the multiple type shown in Figs. 1, 2, 3, and 4, and is designed to be used either for water gas or producer gas. In this apparatus, when producer gas is to be formed and used hot, the regenerators may be entirely cut off by closing the valves 34 and 32 and opening the valves 65 and 66, which are respectively 10 steam valves and air valves, located on one side of the generator and a valve 67, which is a gas outlet valve, located on the other side of the generator, during the blast or flow of the mixture of steam and air in one 15 direction through the generator and opening the other steam, air and exhaust valves when the flow is in the opposite direction. Steam may also be admitted into the pipes 35 through the valves 97. When, however, the 20 producer gas is to be used cold, the valves 65, 66 and 67, are closed, and the valves 32, 34 and 31, and the steam valves 37, also gas outlet valve 46, are manipulated in order to direct the air and steam into the regenerators to heat the air and superheat the 25 steam from whence they are directed into the generator through the proper ports. When the air and steam is directed into the pipe 33 and either through the valves 65 and 30 66 on the one hand, when the producer gas is to be used hot, or when it is directed into the pipe 33 through the regenerator and the valves 32, 31 and 37, it enters the generator from the pipe 33 into the ports 68 and over 35 the upper portion of the incandescent fuel on one side or the other side of the generator according to which of the pipes 33 receives the air and steam. The mixture flows diagonally downward across the generator below 40 the walls 85 to the outlets 69 which causes the blast to pass to the bottom of the incandescent fuel chamber of the generator and directs the gases formed into the pipe 35 on the other side of the generator whence it 45 may be directed either through the regenerator on the said other side, if the producer gas is to be used cold, or it may be directed out through the valve 67 connected to the said pipe 35 when the producer gas is to 50 be used immediately. If desired air and steam may be also directed through the pipe 35 and the ports 69 located on and connected with the same side of the generator that the ports 68 are located on and through which 55 the air and steam is being directed, the gases from the fuel and which are formed by the air and steam coming from the ports 68 and 69 on one side being collected and directed out through the ports 69 on the other side 60 of the generator. This produces a flow of 65 air and steam and of gases of large cross-sectional area through the incandescent fuel, whereby a large quantity of the gas may be formed and whereby a voluminous incandescent fuel bed may be maintained. 70
- In the generator shown in Figs. 8 and 9, I have also provided passageways 70 located near the ash zone 92, and which extend diagonally downward to direct air and steam or steam alone along the upper side of the ashes or substantially along the division line between the incandescent fuel and the ashes. The ends of the passageways form ports for the steam and air which maintain the incandescent fuel of this lower region at the proper temperature to produce a complete combustion of the fuel and yet to prevent the fusion of the ash and the formation of the clinker. 75
- The passageways 70 communicate with the pipes 71 which are connected with the air pipe 30 through the valve 72 and with the steam line through the valve 73 on each side of the generator. The valves 73 and 72 are opened when the air and steam passes through the port 68 on the same side of the generator and if desired also through the port 69 on the same side of the generator, the gases being collected through the port 69 on the other side of the generator. The proportion of the air and steam that is directed through the ports 68 and 69 and the passageway 70 may be varied as desired. I find it preferable, however, to direct more air through the port 68 proportionate to the steam than through the port 69 and more air through the port 69 proportionate to the steam than through the passageway 70 and in fact if desired, very little air may be directed through the passageway 70. 80
- In the construction shown in Figs. 8 and 9, I have provided a port 75 located in a bridging wall 76 that corresponds to the ports 56 in the form of generator illustrated in Figs. 1 and 2 and so that when water gas is produced by the use of the construction illustrated in Figs. 8 and 9, steam may be directed through the pipe 39 which connects, through the valve 77, with the steam line or superheated steam may be directed through the pipe 39 which connects through the valves 38 with regenerators 14 and 15, or the port 75 may be connected through the pipe 39 and the valve 79 with gas exhaust pipe 80 when in the generator it is desired to remove tarry products or hydrocarbon gases from the uncarbonized and partially carbonized fuel, such connection being used either when the generator is being used for the production of water gas or of producer gas. 85
- If it is desired, steam or water may be directed through the pipes 93 into the ashes to quench the ashes before it reaches the shaker member 11. By this arrangement the steam or water used for quenching the 90
- 105
- 110
- 115
- 120
- 125
- 130

ashes may be controlled which prevents spasmodic introduction of steam into the generator by reason of the periodical fall of the ash into the water seal of the trough. 5 The ashes may thus be continuously quenched which results in a continuous introduction of a definite amount of steam into the generator.

The generator illustrated in Figs. 8 and 10 9 is provided with the fuel magazine 82 in which is located the bridge wall 76 which prevents the fuel from becoming packed locally and causes the fuel to be fed loosely into the incandescent chamber. The port 15 75 located in the bridging wall 76 opens downward through a perforated arch 83 (shown in Fig. 11) which prevents the accumulation of portions of the fuel in the 20 openings and thus prevents clogging of the openings.

The fuel 90 is discharged from the fuel magazine 82 into a larger chamber 84 which is formed between two bridging walls 85 that extend down into the incandescent 25 chamber of the generator. The top of the incandescent chamber overhangs the interior of the chamber, and thus leaves passageways or areas that permits the entering air and steam to move laterally over the incandescent fuel 30 91 and consequently greatly extends the area through which the air or steam or both may be introduced into the incandescent fuel. The ports 68 are located in the corner formed by the top wall 95 of the walls 85. 35 This prevents clogging of the ports 68 by the fuel.

The depending walls 85 also afford a similar lateral passageway for movement of the gases to and from the incandescent fuel at a 40 lower region in the incandescent chamber. They bring the lower portions of the paths of the gases down to a low point in the incandescent zone. If, however, it is desired, the same construction can be made 45 with reference to the ports 69; that is to say, portions of the top of the generator may be made in stepped relation and the incandescent chamber enlarged step by step. The ports 69 will then be located in proximity to the incandescent fuel as is the case 50 of the port 68.

In order to prevent the formation of clinkers at the sides or near the lower inner edges of the walls 85, the walls 85 may be 55 provided with ports 86 through which steam may be introduced through the pipes 87 and the valves 88.

When the generator shown in Figs. 8 and 60 9, is to be used for the production of water gas, suitable air valves are opened on one side of the apparatus as for example on the right side of the apparatus during the periods of air flow. Thus air may be admitted through one of the valves 31 to the regenerators 15 and 14 on the right side. It passes

through the regenerators and through pipe 33 and valve 32 and if desired also through pipe 35 and valve 34 thence through port 68 and if through pipe 35 also through port 69 into the generator. It then passes downward 70 and laterally through the fuel bed to the opposite side of the generator, the products passing out through the opposite port 69 and through the other set of regenerators 14 and 15 and through the regenerator stack 75 valve 19 on the left side. During this period air valve 99 on air line 42 on the left side leading to regenerator 14 may be opened to admit secondary air for the combustion of such unoxidized constituents as may exist 80 in the gases and vapors leaving the generator.

During a subsequent steam flow period the stack valve 19 and the air valves 31 and 99 are closed and the steam valve 37 on the 85 right side is opened. The steam is superheated in regenerators 15 and 14 and then passes through the port 68 or ports 68 and 69 through the generator moving in the same direction as the air of the last described period and passing by way of the opposite port 69 and pipe 35 to and through the opposite regenerators 14 and 15. It thence passes by way of valve 46 on the left side of the apparatus to the gas main 47.

During a subsequent period of air flow valves 46 and 37 and also inlet valve 34, are closed and the air valve 31 on the left side of the apparatus is now opened and air admitted to regenerator 15 on the left side. 100 The air then passes through pipe 33 and valve 32 and if desired also through pipe 35 and valve 34 thence to the generator by way of port 68 or ports 68 and 69. It then passes through the generator downward and laterally toward the right side of the generator, the diagonally downward flow crossing the part of the air flow of the preceding period of air flow and the lateral component of flow being reverse to that of the preceding period 105 of air flow. The products thus pass out of ports 69 and pipe 35 and valve 34 to regenerators 14 and 15 all positioned on the side of the regenerator opposite to that to which the products of the first period were directed, such products passing finally to the other stack valve 19 on the right side. During 110 this period air valve 99 on the right side in the air 42 leading to regenerator 14 may be opened to admit secondary air for the combustion of unoxidized gases and vapors leaving the generator.

The last mentioned stack valve 19 and the air-blast valves 31 and 99 are closed and steam is admitted by way of valve 37 on 125 the left side. The flow of steam through the steam flow period is through the regenerators 15 and 14 and the flow of steam and gas through the generator as well as the flow of gas through the other regenerators 14 and 130

15 being all substantially through the same paths as the air and products of the preceding period of air flow. The gas finally passing into gas main 47 by way of valve 46 on 6 the right side of the apparatus.

Valve 73 for steam admission or valve 72 for air admission may be opened to admit steam or air through pipe 71 and port 70 when the port 68 on the corresponding side

10 of the generator is opened, the resultant reaction products passing out with the other reaction products arising from the flow from the ports 68 and 69 to the opposite side of the generator through the opposite port 69.

15 The sequence of the periods above described may be changed to suit quality of the fuel or condition of the heat or according to the gas required.

As indicated very generally in Fig. 10 the 20 air and steam flows may be greatly varied in order that the maximum efficiency of gas production may be accomplished by either of the generators. In addition to the air flow, the steam flow, or the mixture of air 25 and steam flow indicated in Fig. 10, the volatile gases may be exhausted by connecting an exhausting means with the passageways that lead to the ports 56 of the generator shown in Fig. 1 or to the ports 75 shown 30 in Fig. 9. Or superheated steam may be directed from certain ports, such as ports 56 and 75 through the colder fuel to carry down hydrocarbon materials for further cracking. These latter operations may be performed in 35 conjunction with any of the operations indicated in Fig. 10.

Air is admitted through one set of ports 40 52 and moves diagonally downward toward a set of ports 53, the said set of ports 53 being located in walls or bridges that are located next in order to the walls or bridges in which the said ports 52 are located, the currents moving preferably laterally. Steam is then admitted through the said ports 52 45 and the gases are expelled from the said ports 53, the general movement being also laterally. In the subsequent period the streams of air flow from the ports 52 to the ports 53 in a general lateral opposite direction. Preferably the steam follows the air paths of the preceding period, so that the order would be, the formation of air streams in a general lateral or diagonally downward direction towards one side of the generator 50 55 or division of a generator as in Fig. 1 while these streams are followed by steam streams in the same general direction, and then followed by air streams in a general lateral or diagonally downward direction towards the other side of the generator division or unit. The air streams are followed again by steam streams that follow the same paths. Also air may be allowed to pass out of ports 53 to ports 53 of the neighboring walls or 60 65 bridges toward which air may be flowing 65

from the ports 52 located directly above the first named ports 53. Streams of air will then be caused to move in a substantially horizontal direction across the generator as well as diagonally downward. Steam streams 70 may be also directed along the substantially horizontal paths of the air streams of the preceding period. Each period of the steam streams preferably follow a period of the flow of the air streams. When the generator 75 is reversed, that is, when the movements of the air and the products of combustion through the regenerators are reversed, the horizontal movement of the air from one port 53 towards a port 53 of an adjoining bridge or wall is reversed in direction. This 80 may be followed by streams of steam in the succeeding period. Variations of the diagonal flow of air and steam and of horizontal streams of air and steam and variations 85 in their sequence may be utilized to produce the desired results, that is, according to the character of the fuel and according to the condition of the ash, and according to the gases obtained. Also mixtures of air and 90 steam may be used during the steam or airblast periods.

In the diagram shown in Fig. 10 the air and steam streams and mixture of air and steam streams from one set of upper openings of the bridges and walls of the generator are marked respectively *a*, *s*, and *a* and *s*. Any one of these streams will pass through the coal during certain periods, that is, the steam stream will follow the period during which the air stream flows or the air and steam mixture stream follows the period during which the air flows. The other crossing streams will follow the period of the steam stream or of the air and steam stream marked *s* or *a* and *s*. These latter or subsequent acting streams are marked *a'*, *s'* and *a'* and *s'*. These streams will likewise follow in the same order, that is, the *s'* stream will follow the *a'* stream or the *a'* and *s'* stream 105 will follow the *a'* stream. Following this plan the *a'* stream will then follow either the *s'* stream or the *a'* and *s'* stream, and so on the cycles of the generator will be carried out. 110

If desired, streams may be directed laterally that is, in a horizontal direction, while the other streams are being directed in a general lateral direction. By general lateral direction is meant a lateral direction or a diagonal direction, as for example, when the *a* stream is flowing the *a''* stream may be flowing from the lower openings of the bridges or wall in which the openings are located from which the *a* streams are flowing. While the *s* stream or the *a* and *s* stream is flowing the *s''* stream or the *a''* and *s''* may be flowing in the same general lateral direction. Also while the *a'* stream is flowing air may be also flowing along the line *a'''*, which is in a lateral direction re- 115 120 125 130

verse to that of the a'' stream. The same is true with respect to the s'' streams or the a''' and s''' streams. The gases are being drawn or emitted from the lower openings of the alternate bridges, while air during one period and steam during a subsequent period, or a mixture of air and steam during such subsequent period is being directed or forced into an upper opening. This produces the general lateral movement of the gases and particularly the diagonal movement.

The air or steam, or air and steam, or a mixture of air and steam, are directed through the fuel in different stages of operation within the generator laterally with respect to the side or sides of the generator. The generators shown in the drawings are rectangular in plan and consequently, laterally or in a general lateral direction are broad terms to cover movements towards the sides, or the side of the generator or generator division. The terms laterally, or in a lateral direction includes the more specific terms "diagonally", and "horizontally". The streams are so directed as to carry the air or steam, or both, across the fuel bed or portions thereof as heretofore described, or specifically through the incandescent fuel, or as may be particularly pointed out in the specification and claims. The crossing or counter-movement of the streams produce the desired results with reference to the maintenance of the reaction zone, and to the securing of efficient production of the gas or of a gas having a desired mixture of vapor and gas. As pointed out herein, and shown in Fig. 10 of the drawings, the operation of the generator may be divided into four periods that repeat, it being understood, however, that changes may be made in the proportion and the quantity of the air or steam, and the length of time of each of the periods and the sequence of the periods according to the effects produced in the generator. Ordinarily, the process would follow the repeated steps or cycles that are as a matter of fact divided into the said four periods of operation. The steps successively repeat themselves while the periods in each step preferably follow the same order. First air may predominate and is directed through the generator or generator division toward the alternate wall or walls. This period of flow is followed by a period during which steam predominates and is directed toward the other wall or walls of the generator or division of the generator, that is, it is directed to the wall or walls located opposite the wall or walls toward which the air stream of the first period was directed. The third period is followed by a fourth period wherein steam may predominate and in which the paths are in general laterally reverse in direction to those in which the air of the third period was directed. The next step or cycle then begins

with the first period and so on, the generator being operated through the succeeding periods. As pointed out and referred to in the claims, air and steam may be directed in the generator during the same periods to obtain the best working conditions of the generator, but generally speaking, the predominating element namely, the air or steam is directed into the generator during alternate periods, and these periods, in pairs alternate as to the general lateral direction in which the streams move. Also the periods may be subdivided by cessation of the streams, that is, there may be in the same period a plurality of succeeding streams of air that follow substantially the same path or succeeding streams of steam that flow substantially in the same path to give opportunity for the desired reaction in the generator.

I claim:

1. The method of producing water gas, which consists in periodically passing a plurality of streams of air in a direction substantially diagonally downwardly through incandescent fuel, and then passing a plurality of streams of steam through the paths of the air streams during periods following the periods of the air stream flow, the paths of different periods of the air stream flow crossing each other.

2. The method of producing gas, which consists in periodically passing a plurality of streams of air in a direction substantially diagonally downwardly through incandescent fuel, and then passing a plurality of streams of air and steam along the paths of the air streams of the preceding periods, the paths of the alternating periods of the air stream flow crossing each other.

3. The method of producing water gas, which consists in periodically passing streams of air substantially diagonally downwardly through incandescent fuel and other streams of air laterally through incandescent fuel during the same periods of the diagonally-directed air flow, and then periodically passing streams of steam along the paths of the air flow of the preceding periods, the paths of the diagonal streams of succeeding periods of air flow crossing each other, and the direction of the lateral streams of succeeding periods of air flow being in opposite general lateral directions through the incandescent fuel.

4. In the method of producing gas, the steps which consist in passing streams of air substantially diagonally downwardly through incandescent fuel and separate streams of air laterally, and then passing streams of air and steam diagonally downwardly and other streams of air and steam laterally during periods succeeding to the movement of the first named streams of air, the paths of movements of the streams of air and steam following the paths of move-

ments of the first named streams of air during the preceding periods.

5. In the method of producing gas, the steps which consist in passing streams of air and streams of steam substantially diagonally downwardly through incandescent fuel during successive periods, and then passing streams of steam laterally through the incandescent fuel during the periods that the steam is also directed diagonally downward.

6. The method of producing gas, which consists in passing streams of air substantially diagonally downwardly through incandescent fuel during different periods, the

15 paths of movements of the air during said periods crossing each other; and then passing lateral streams of steam into the incandescent fuel during periods intermediate the periods of the flow of the air.

20 7. The method of producing water gas, which consists in passing streams of air laterally through incandescent fuel and in generally opposite directions during different periods, and then passing streams of steam substantially diagonally downwards through the fuel during periods intermediate the periods at which the air is directed laterally.

8. In the method of producing gas, the steps which consist in passing streams of a 30 mixture of air and steam substantially diagonally downwardly through incandescent fuel having an ash zone, the paths of the streams of the mixed air and steam crossing each other during successive periods, and then passing streams of steam into the incandescent fuel near the ash zone in the same general lateral directions in which the streams of the mixture of air and steam flow.

40 9. The method of producing water gas, which consists in passing streams of air diagonally downwardly for blasting a fuel bed to incandescence, and then passing streams of steam through the paths of the said air streams and other streams of steam laterally through the incandescent fuel, the said steam streams flowing during periods that alternate with the periods of the flow of the air streams and the laterally flowing steam streams moving in the same general direction laterally that the diagonally flowing streams of steam flow.

50 10. The method of producing water gas, which consists in passing a plurality of streams of air diagonally downwardly and in a general lateral direction for blasting a fuel bed to incandescence, and then passing a plurality of streams of steam diagonally downwardly and in a general lateral direction through the incandescent fuel, the said steam streams flowing during periods that alternate with the periods of the flow of the said air streams and the said streams of air and streams of steam moving during two

succeeding periods in the same general lateral direction.

65 11. The method of producing water gas, which consists in passing streams of air and steam diagonally downwardly through incandescent fuel and during separate periods, the streams of steam taking the same paths as the air streams, the paths of streams of air of subsequent periods of air flow crossing each other, and passing separate streams of steam downwardly into the fuel from above the entrance of the air during the periods that the first named steam streams are passed into the fuel.

70 12. The method of producing water gas, which consists in passing streams of air diagonally downwardly through incandescent fuel and simultaneously admitting streams of air laterally, then passing streams of steam diagonally downwardly and streams of steam laterally during periods subsequent to the movement of the air, the diagonal streams of subsequent periods of air flow and steam flow crossing each other, the lateral streams of air and steam of subsequent periods moving in opposite directions, and passing separate streams of steam into the fuel from above the entrances of the said air and steam streams and downwardly into the incandescent fuel during the periods that the first named steam streams are directed into the fuel.

75 13. The method of producing water gas, which consists in passing air substantially diagonally downwardly through incandescent fuel during alternate periods, and then passing steam laterally during periods between the periods of the air flow, the paths of the air streams during succeeding periods of air flow crossing each other and the movement of the steam during succeeding periods of steam flow being in opposite directions, the steam flow during each period succeeding the air flow being in the same general lateral direction of the said air flow of the preceding period.

80 14. In the method of producing water gas, the steps which consist in passing a plurality of streams of steam substantially diagonally downwardly through incandescent fuel during alternate periods, and then passing a plurality of streams of air laterally during periods between the periods of steam flow, the movement of the air during the periods of air flow being in the same general lateral direction in which the steam flow moves during the preceding period.

85 15. The method of producing water gas, which consists in passing air substantially diagonally downwardly through incandescent fuel during alternate periods, and then passing steam diagonally downwardly during the periods between the periods of air flow, the steam flow following the paths of

the air flow of the preceding period and the air flow of the succeeding periods of air flow crossing each other, and passing air laterally through the incandescent fuel during the 5 said periods of air flow and in the same general lateral direction as the diagonal streams of air flow of each period of air flow.

16. The method of producing water gas, which consists in passing streams of air diagonally downwardly through incandescent fuel and laterally through incandescent fuel and in the same general lateral direction during alternate periods, the diagonal streams of air flow crossing each other, 15 and then passing steam laterally through incandescent fuel during the periods between the periods of air flow, the direction of the lateral streams of steam flow being in the same direction as the lateral stream of air 20 flow of the preceding period.

17. A method of producing water gas, which consists in substantially diagonally downwardly air blasting a fuel bed in a gas generator by a plurality of air streams to 25 incandescence, the air entering the generator below the level of the top of the fuel in the generator, then substantially diagonally downwardly steam blasting the fuel by a plurality of streams of steam, the steam 30 entering below the level of the fuel in the generator, then diagonally downwardly air blasting the fuel whereby the path of the air crosses the path of the preceding air blast, and then diagonally downwardly 35 steam blasting the fuel.

18. A method of producing water gas, which consists in diagonally downwardly air blasting the fuel bed to incandescence by a plurality of streams of air, then diagonally 40 downwardly steam blasting the fuel by a plurality of streams of steam, the steam blast moving through the same paths that the preceding air blast moved, then diagonally downwardly air blasting the fuel 45 whereby the path of the air crosses the path of the preceding air blast, and then diagonally downwardly steam blasting the fuel, the last named blast following the path of the preceding air blast.

50 19. A method of producing water gas, which consists in diagonally downwardly air blasting a fuel bed to incandescence and at the same time air blasting by streams of air moving substantially horizontally through 55 the fuel bed and in the same general lateral direction as the diagonally downwardly moving air, then diagonally downwardly and laterally steam blasting the fuel by streams of steam that move diagonally 60 downwardly and substantially horizontally and in the same general lateral direction that the air moved in the preceding period, then diagonally downwardly air blasting the fuel and laterally by separate streams of

air that move diagonally and substantially 65 horizontally whereby the diagonally downwardly moving air stream crosses the path of the preceding diagonal air blast and the substantially horizontal air streams move opposite to that of the streams of air of the 70 preceding air blast, and then diagonally downwardly and horizontally steam blasting by separate streams of steam that move diagonally downwardly and substantially 75 horizontally.

20. A method of producing water gas, which consists in passing air into incandescent fuel, then blasting with a plurality of streams of a mixture of air and steam passed diagonally downwardly into the fuel 80 bed, then passing a plurality of streams of air into the incandescent fuel, and then diagonally downwardly blasting with a mixture of air and steam whereby the path of the mixture of air and steam crosses the 85 path of the preceding blast of a mixture of air and steam.

21. A method of producing water gas, which consists in air blasting the incandescent fuel bed, then diagonally downwardly 90 blasting the fuel with a mixture of air and steam and blasting the fuel with steam moving substantially horizontally through the incandescent fuel near the ash zone in the same general lateral direction of the 95 diagonally downwardly moving mixture of air and steam, then air blasting the incandescent fuel, and then blasting the fuel with a mixture of air and steam, moving diagonally downwardly and by streams of steam 100 that move through the incandescent fuel near the ash zone in the same general lateral direction in which the streams of the mixture of air and steam flow.

22. The method of producing water gas, which consists in diagonally downwardly air 105 blasting a fuel bed having a lower ash zone to incandescence by a plurality of streams of air, and then diagonally downwardly and substantially horizontally steam blasting the fuel by a plurality of streams of steam, then diagonally downwardly air blasting the fuel whereby the path of the air crosses the path of the preceding air blast, and then diagonally 110 downwardly and substantially horizontally steam blasting the fuel, the substantially horizontally moving steam blasts being located near the ash zone of the fuel.

23. The method of producing water gas, which consists in diagonally downwardly air blasting a fuel bed having a lower ash zone to incandescence, then diagonally 115 downwardly steam blasting the fuel along the paths of the air blast of the preceding period, and steam blasting substantially horizontally along the top of the ash zone, then diagonally downwardly air blasting the 120

fuel whereby the path of the air crosses the path of the preceding air blast, and then diagonally downwardly steam blasting the fuel along the path of the preceding air blast and steam blasting the fuel along the top of the ash zone, the substantially horizontally moving steam blasts produced by steam moving in the same general lateral direction as the diagonally downwardly moving steam in each of the steam blast periods.

In testimony whereof I have hereunto signed my name to this specification.

LOUIS B. MOORHOUSE.
